UNITED STATES PATENT OFFICE

WALTER H. MAYHEW, OF TORONTO, OHIO

APPARATUS FOR HANDLING UNBURNED CLAY PIPES

Application filed July 12, 1928. Serial No. 292,175.

This invention is an improvement upon the apparatus shown and described in Letters Patent of the United States No. 1,395,588, granted November 1, 1921, and consists in features of structure adapting the apparatus to the handling of relatively small pipe, that is to say, pipe of 12 to 20 inches in diameter and 2 feet in length. The apparatus of the patent referred to is adapted to the handling of pipe of from 24 to 36 inches in diameter, and could not be economically used for the handling of such smaller pipe as that now contemplated, because it is incapable of sufficient rapidity of operation.

In the accompanying drawings the apparatus of my present invention is illustrated. Fig. I is a view in plan from above; Fig. II, a view in side elevation; Fig. III, a view in vertical and longitudinal section; and Fig. IV, a view in end elevation.

As in the Letters Patent alluded to above, the apparatus of the present invention includes a cradle 1, mounted to rotate on a horizontal axis, and is shown to be trunnioned in opposite stationary supports 2. The axis of the cradle is a medial axis; that is to say, it is disposed in the interval between the planes which define the opposite ends of the cradle. The cradle consists of a suitable framework 30 of cubical form, open on one side (the side to the left, Figs. I, II, and III), and conveniently containing within the framework a block or seat 3 of semi-cylindrical shape and of such size as to engage the cylindrical surface 35 of a length of pipe, and properly to support it in the manner presently to be described. This cradle is further provided at its opposite ends, the top and bottom, as seen in Figs. I and III, with two sets of idly turning rollers 4. The faces of the rollers of each of these two sets lie in common plane, and the two planes are spaced apart a distance slightly greater than the over-all height of the length 40 of pipe to be handled, together with the blocks presently to be described.

In the frame of my earlier patent the seat for the pipe was within a limited space longitudinally movable. This feature does not exist in the frame of my present invention.

The frame of my earlier patent was mounted

for rotation at a point below its horizontal center. In this respect also the frame of my present invention differs, for it is trunnioned in the horizontal plane midway of its height. It is, however, so proportioned that when 55 swung from the vertical position in which in Figs. II, III, and IV it is shown, to horizontal position, it will in that position be balanced, but if it be moved from such horizontal position either way, it will tend to 60 swing toward vertical position in one direction or the other. In short, the center of gravity of the empty and unloaded frame is to the left, as seen in Figs. II and III.

Associated with the swinging cradle 1 are 65 feed tables equipped with idly turning rollers 5 whose upper surfaces extend in common plane, and with such plane the two sets of rollers 4 of the swinging frame 1 coincide as the cradle comes to each of its alternate vertical positions. Secured to the table frame are two cross bars 11 and 11' which are adapted to serve as stops, and stay the cradle 1 in one or the other of its two vertical positions. That is to say, in the position in which the cradle 1 is shown in the drawings, the corner portions 12' of the cradle rest upon the stop or bar 11', and in its inverted position, the corner portions 12 of the cradle rest upon the stop 11. Thus, it will be seen that the stops 75 11 and 11' insure the arrest of the cradle in either of its vertical positions.

Figs. II, III, and IV of the drawings 80 show a length of pipe P in position in the cradle, ready for inversion. The length of pipe may be understood to be formed of clay, and to be still in green, that is to say, in unburnt condition. In such condition it is frail, easily damaged, and must be handled with care and with precision. Referring 85 particularly to Fig. III the length of pipe is seen to be resting, flanged end down, upon a stool 6, with a cylindrical boss 7, which boss enters and fits snugly within the bore of the flanged end. It is upon such a stool that the 90 length of pipe comes from the shaping press, and it is the length of pipe so supported which is to be inverted and without injury brought to rest upon its smaller, opposite, 95 unflanged end.

The stool 6 is provided on its under surface with strips or skids 8, upon which it engages the supporting surface. These skids are preferably two in number and the organization is such that as the length of pipe supported upon the stool comes to position and advances to the inverting apparatus, the skids 8 extend in the direction of the length of the conveyor tables and perpendicular to the rollers 5 (and to the rollers 4 also) which constitute the tables. By such particular provision the advance of the laden stool to the inverting apparatus is facilitated.

When the length of pipe has been shaped and rests upon its stool 6, a board 9 is laid upon its upper end. This board is of substantially the same outline with stool 6, it may however be formed without a cylindrical boss, such as the boss 7 of the stool. It is provided with strips 10 of the same character as and adapted to serve similar ends as the skids 8 of stool 6. When the board 9 is applied the strips 10 are uppermost, and the board is applied in such position that they extend in parallelism with the skids 8. The cradle is so proportioned that the space between its opposite sets of rollers 4 is slightly greater than the over-all distance from the lower surface of skids 8 to the upper surface of strips 10.

In operation, when a length of pipe has been shaped and rests upon a stool 6, a board 9 is laid upon it, properly centered and with its strips 10 extending in the direction indicated. The length of pipe is then advanced over the rollers 5 of the feed table from left to right, as seen in Figs. I, II, and III, until it comes to the position shown in Figs. II and III in the cradle 1, previously swung to the position to receive it. In this position the stool has passed from the rollers 5 and rests wholly on the rollers 4 at the then lower end of the cradle 1, and the cylindrical face of the length of pipe has come to position within the seat 3. The cradle then is swung clockwise on its trunnions, as seen in Figs. II and III, through a half revolution. In this turning the seat 3 underlies and supports the length of pipe, and as the cradle comes to its alternate vertical position the inverted pipe comes to rest on its smaller end, now the lower end, and upon board 9. Board 9 in turn rests on the rollers 4 of the opposite end of the cradle. The slight longitudinal movement of the length of pipe, incident to its inversion, has had no effect to injure it. When so overturned, the length of pipe resting on board 9 is run out on rollers to the right, and the stool 6 is removed from its then upper end. The length of pipe then remains in desired position for further dealing with it.

When the inverted pipe has been run out upon the table to the right, the cradle may be turned back counter-clockwise to its ini-

itial position, ready to receive another length of pipe. The inverting apparatus is adapted to operation at relatively high speed, so as to constitute no obstruction in the course of rapid pipe production; and it is the roller support of the pipe lengths which makes possible such facility of operation.

I claim as my invention:

Pipe inverting apparatus including a framework of cubical form open on one side, trunnioned on a horizontal axis midway its length and adapted to swing between opposite positions in which it stands vertically and open in one or the other of two opposite directions, its center of gravity being remote from the trunnion axis in direction toward such open side.

In testimony whereof I have hereunto set my hand.

WALTER H. MAYHEW.
